(57) **CLAIM**

The ornamental design for a device housing, as shown and described.

DESCRIPTION

FIG. 1 is a top plan view of the device housing, in accordance with our design;

FIG. 2 is a front elevation view thereof;

FIG. 3 is a bottom plan view thereof;

FIG. 4 is a first side elevation view thereof;

FIG. 5 is a rear elevation view thereof; and,

FIG. 6 is a top perspective view thereof showing a front, top, and first side.

The broken lines throughout the drawings are included for the purpose of illustrating portions of the device housing that form no part of the claimed design.
